UNITARY LAMP SOCKET SUPPORTING
STRUCTURE

George J. Thomas, Birmingham, Mich., assignor
to Watts Electric & Mfg. Co., Birmingham,
Mich., a corporation of Michigan

Application November 26, 1948, Serial No. 62,187

5 Claims. (Cl. 173—339)

1

The present invention relates to an improved lamp socket supporting fixture adapted to be releasably mounted on a suitably apertured supporting plate or bracket.

It is an object of the invention to provide an improved lamp socket supporting fixture which is simple in construction, economical of manufacture and reliable and efficient in operation.

A further object of the invention is to provide an improved lamp socket supporting fixture adapted to receive and support an associated lamp socket member and having improved means for securing the fixture to a suitably apertured plate or supporting member.

Another object of the invention is to provide such a lamp socket supporting fixture consisting of a single element having cooperating portions adapted to releasably mount the fixture on a suitably apertured supporting plate or member.

Other and more detailed objects of the invention will become apparent from a consideration of the following specification, the appended claims and the accompanying drawing, through the several views of which like reference characters designate like parts, and wherein:

Figure 1 is a broken sectional view showing a lamp socket supporting fixture embodying the present invention mounted in an associated supporting plate and supporting an illustrative lamp socket and lamp;

Fig. 2 is a plan view of the lamp socket supporting fixture illustrated in Fig. 1, showing in broken lines an associated supporting plate;

Fig. 3 is a broken sectional view of the construction illustrated in Fig. 2 taken along the line 3—3 thereof;

Fig. 4 is an elevational view of the construction illustrated in Fig. 2, looking in the direction of the arrow 4;

Fig. 5 is an elevational view of the construction illustrated in Fig. 2 looking in the direction of the arrow 5;

Figs. 6 and 7 are sectional views of the construction illustrated in Fig. 2 taken along the lines 6—6 and 7—7 thereof respectively; and,

Fig. 8 is a broken elevational view showing an apertured supporting member adapted to receive and mount the applicant's lamp socket supporting fixture.

Referring to the drawings, the applicant's lamp socket supporting fixture, generally indicated at 10, is adapted to be supported in a supporting plate or bracket 12 having an aperture including a circular portion 14 and a pair of opposed notches 16 communicating with the circular por-

2

tion 14 and extending radially outwardly thereof. The lamp socket supporting fixture 10 has a tubular portion 18 adapted to receive and support the inner end of a lamp socket member 20.

5 It will be appreciated from a complete understanding of the present invention that the lamp socket member 20 may be of any suitable design and may be secured in the cylindrical portion 18 of the lamp socket supporting fixture 10 in any suitable manner. For illustrative purposes, the lamp socket 20 is tubular and open at both ends, and is provided with J-slots 22 and 24 adapted to effect a bayonet and slot construction with the base of a lamp 26 having outwardly projecting trunnions 28. In the preferred embodiment illustrated, the inner end portion of the lamp socket 20 is telescopically received in and has a press fit with the cylindrical portion 18 of the lamp socket supporting fixture 10. At the end 10 of the tubular portion 18 adjacent the inner end of the lamp socket 20 the fixture 10 has an integrally formed end wall 30 having an aperture 32 through which may extend a suitable electrical connector means 34. The end wall 30 is adapted 15 to seat one end of a coil spring 36, the other end of which in accordance with conventional practice engages a plunger 38 carrying an electrical terminal 40 and slidably longitudinally of the lamp socket 20.

20 At the opposite end of the tubular portion 18, the lamp socket supporting fixture 10 terminates in an integrally formed radially outwardly extending flange generally indicated at 42. Adjacent the cylindrical portion 18 of the fixture 10, the flange 42 is shaped to define an annular axially offset portion 44. This offset portion 44 affords an axially outwardly projecting boss 25 adapted to project into and fit the circular portion 14 of the aperture in the supporting member 12 and cooperate with the supporting plate 12 to accurately locate the lamp socket supporting fixture 10 relative thereto. Radially outwardly of the axially offset portion 44 the flange 42 defines a generally annular axially outwardly presenting surface 46 adapted to engage one side of the supporting plate member 12 adjacent the aperture therein.

25 The flange 42 is also provided with circumferentially spaced, generally radially extending slots 47 and intermediate said slots is shaped to define a pair of diametrically opposed fingers 48 extending radially outwardly from the axially offset portion 44 and offset axially outwardly relative to the surface 46. These fingers 48 have 30 axially inwardly presenting surfaces 50 (best

55

illustrated in Figs. 4, 5 and 6) adapted to engage the opposite side of the supporting plate 12 as hereinafter more fully described.

The proportions of the fingers 48 are such that when the lamp socket supporting fixture 10 is placed against the plate member 12 with the fingers 48 aligned with the notches 16, the annular portion 44 will project into the circular portion 14 of the aperture in the plate member 12, the flange surface 46 will engage the adjacent surface of the plate 12, and the fingers 48 will be disposed in position for the surfaces 50 thereof to engage the remote side of the plate 12 upon rotation of the fixture relative to the plate member. To provide a resilient gripping of the plate member 12 between the surfaces 46 on the flange 42 and the oppositely presenting surfaces 50 on the fingers 48, the normal axial spacing between these surfaces is preferably slightly less than the thickness of the plate member 12. Also, the lateral edges at opposite sides of the fingers 48 are preferably outwardly turned as illustrated at 52 (see Figs. 4 and 6) to insure that the fingers 48 will be cammed up onto the plate member 12 upon rotation of the lamp socket supporting fixture 10 relative to the plate member.

In the preferred embodiment illustrated, the flange 42 is shaped to provide a pair of opposed detents 54 spaced circumferentially of the flange relative to the fingers 48 and adapted upon rotation of the fixture 10 relative to the plate member 12 during mounting of the former on the latter, to drop into the notch portions 16 of the aperture in the plate member and engage the adjacent edge portions of the plate member to yieldably prevent rotation of the fixture relative to the plate member.

It will now be appreciated that to mount the lamp socket supporting fixture 10 upon the plate member 12 it is only necessary to align the fingers 48 with the notch portion 16 of the aperture in the plate member, move the fixture through the aperture until the flange surfaces 46 engage the adjacent side of the plate, during which the fingers are inserted into and substantially through the notches 16, and then rotate the fixture 10 relative to the plate member 12 until the detents 54 snap into the notches 16, it being appreciated that during such rotation the fingers 48 are cammed up onto the remote surface of the plate 12 and the latter is resiliently gripped between the surfaces 50 on the fingers 48 and the oppositely presenting surfaces 46 on the flange 42. Similarly, to remove the fixture 10 it is necessary only to apply a sufficient rotative force to the fixture 10 to cam the detents 54 out of the notches 16 and rotate the fixture 10 relative to the plate 12 until the fingers 48 are aligned with the notches 16 at which time the fixture may be readily withdrawn from the plate.

While only one embodiment of the invention has been illustrated and described in detail it will be readily appreciated by those skilled in the art that various modifications and changes may be made without departing from the spirit of the present invention.

What is claimed is:

1. A unitary lamp socket supporting fixture adapted to be secured to a supporting element having an aperture including a circular portion and a notch portion extending radially outwardly of said circular portion, said fixture comprising a tubular portion adapted to receive a lamp socket member and terminating at one end in an outwardly turned flange having an annular

lar axially offset portion adjacent said tubular portion adapted to project into and substantially fit said circular portion of said aperture, said flange, outwardly of said annular portion, being shaped to define an axially presenting surface adapted to engage one side of said element and a radially extending finger having an axially spaced and oppositely presenting surface, said finger being adapted to be inserted through said notch portion of said aperture in one rotative position of said fixture relative to said element and said fixture being adapted in another rotative position of said fixture relative to said element to be held against axial movement by the engagement of said surfaces at opposite sides of said element, said flange, outwardly of said annular portion, having an axially offset portion angularly spaced from said finger and adapted in one rotative position of said fixture relative to said element, to project into said notch portion of said aperture to engage said element at opposite sides of said notch portion of said aperture to yieldably hold said fixture against rotation relative to said element, the radial distance to the outer limit of said last named axially offset portion being the same as that to the outer limit of said finger.

2. A unitary lamp socket supporting fixture adapted to be secured to a supporting element having an aperture therein, including a circular portion and a notch portion extending radially outwardly of said circular portion, said fixture having a tubular portion adapted to receive a lamp socket member and terminating at one end in an integrally formed flange extending radially outwardly therefrom generally at right angles to said tubular portion, said flange including an annular radially inner flange portion extending radially outwardly from said tubular portion, a radially outer flange portion spaced axially of said tubular portion from said inner flange portion and extending radially outwardly from said inner flange portion, and an intermediate portion connecting said inner and outer portions and adapted to closely fit said circular portion of said aperture to locate said fixture relative to said supporting element, said flange having a pair of closely spaced substantially parallel slots extending inwardly from the periphery thereof, the portion of said flange intermediate said slots being spaced axially of said tubular portion relative to said outer flange portion and being adapted to co-operate therewith to engage opposite surfaces of said supporting element.

3. A unitary lamp socket supporting fixture adapted to be secured to a supporting element having spaced parallel and oppositely facing surfaces and an aperture opening through said surfaces, said fixture being formed of a single sheet metal stamping and having a tubular body portion adapted to receive a lamp socket and terminating at one end in an outwardly turned flange consisting of generally flat radially inner and outer portions extending at right angles to said tubular body portion and spaced axially of said body portion relative to each other and an intermediate portion interconnecting said radially inner and outer portions and adapted to project into and substantially fit said aperture, said outer flange portion having a surface adapted to engage one of said parallel surfaces and having a pair of spaced and substantially parallel slots extending inwardly from the periphery thereof, and the portion of said outer flange portion between said slots being spaced axially of said tubular body

portion relative to said surface of said outer flange portion and constituting a finger having a surface adapted to engage the other of said parallel surfaces.

4. A unitary lamp socket supporting fixture adapted to be secured to a supporting element having an aperture including a circular portion and a notch portion extending radially outwardly of said circular portion, said fixture being formed of a single sheet metal stamping and comprising a tubular portion adapted to receive a lamp socket member and terminating at one end in an outwardly turned flange having an annular axially offset portion adjacent said tubular portion adapted to project into and substantially fit said circular portion of said aperture, said flange, outwardly of said annular portion, being shaped to define an axially presenting surface adapted to engage one surface of said element, said flange outwardly of said annular portion having a pair of spaced and substantially parallel slots extending inwardly from the periphery thereof, and the portion of said flange between said slots being spaced axially of said tubular portion relative to said axially presenting surface and constituting an integrally formed radially extending finger having an axially spaced and oppositely presenting surface, said finger extending substantially radially outwardly beyond said annular axially offset portion and having its opposite edge portions adjacent said slots deformed in a direction away from said axially presenting surface, said finger being adapted to be inserted through said notch portion of said aperture in one rotative position of said fixture relative to said element and said fixture being adapted in another rotative position of said fixture relative to said element to be held against axial movement by the engagement of said surfaces at opposite sides of said element.

5. A unitary lamp socket supporting fixture adapted to be secured to a supporting element having an aperture including a circular portion and a notch portion extending radially outwardly of said circular portion, said fixture being formed of a single sheet metal stamping and comprising a tubular portion adapted to receive a lamp socket member and terminating at one end in an outwardly turned flange having an annular axially offset portion adjacent said tubular portion adapted to project into and substantially fit said circular portion of said aper-

ture, said flange, outwardly of said annular portion, being shaped to define an axially presenting surface adapted to engage one surface of said element, said flange outwardly of said annular portion having a pair of spaced and substantially parallel slots extending inwardly from the periphery thereof, and the portion of said flange between said slots being spaced axially of said tubular portion relative to said axially presenting surface and constituting an integrally formed radially extending finger having an axially spaced and oppositely presenting surface, said finger extending substantially radially outwardly beyond said annular axially offset portion and having its opposite edge portions adjacent said slots deformed in a direction away from said axially presenting surface, said finger being adapted to be inserted through said notch portion of said aperture in one rotative position of said fixture relative to said element and said fixture being adapted in another rotative position of said fixture relative to said element to be held against axial movement by the engagement of said surfaces at opposite sides of said element.
